DESIGN FOR A HEADDRESS

Kenneth C. Hamilton, Milwaukee, Wis., assignor to Milwaukee Lace Paper Company, Milwaukee, Wis., a corporation of Wisconsin

Application July 7, 1933. Serial No. 48,654

Term of patent 3½ years

To all whom it may concern:

Be it known that I, KENNETH C. HAMILTON, a citizen of the United States, residing at Milwaukee, in the county of Milwaukee and State of Wisconsin, have invented a new, original, and ornamental Design for a Headdress, of which the following is a specification, reference being had to the accompanying drawing forming a part thereof.

The figure is a view of a headdress showing my new design.

The headdress comprises a sheet of paper or the like, shaped and ornamented in the manner shown, and adapted for application to and across the forehead of a wearer. It is provided adjacent its lower edge with a series of slots 10, through which an attached ribbon may be threaded and fixed about the head.

I claim:

The ornamental design for a headdress, substantially as shown and described.

In witness whereof, I hereunto subscribe my name this 29th day of June, 1933.

KENNETH C. HAMILTON.
